UNITED STATES PATENT OFFICE.

EDWARD F. DALTON, OF WATERFORD, NEW YORK, ASSIGNOR OF ONE-HALF
TO WILLIAM F. HOLROYD, OF SAME PLACE.

AXLE CUTTER AND THREADER.

SPECIFICATION forming part of Letters Patent No. 311,647, dated February 3, 1885.

Application filed August 4, 1884. (No model.)

To all whom it may concern:

Be it known that I, EDWARD F. DALTON, a citizen of the United States, residing at Waterford, in the county of Saratoga and State 5 of New York, have invented certain new and useful Improvements in Tools for Shortening and Cutting Screw-Threads upon Axle-Spindles, of which the following is a specification, reference being had therein to the accompanying drawings.

My invention relates to improvements in the construction of tools for shortening and cutting additional screw-threads upon axle-spindles, to compensate for the wear of the 15 boxes.

The object of my invention is to furnish a simple and inexpensive tool to be employed upon any-sized spindle; and the invention consists in certain features of construction 20 hereinafter described, and specifically set forth in the claims.

Referring to the drawings, Figure 1 is a front view of the tool. Fig. 2 is a central longitudinal section, upon a larger scale, of the central portion of the same. Fig. 3 is a transverse section on line $x-x$ of Fig. 1. Fig. 4 is a perspective view of one of the cutters. Fig. 5 is a perspective view of both cutters placed in juxtaposition, but removed from the stock. 30 Fig. 6 is a side view of a portion of an axle-spindle upon which this tool may be used.

Like letters indicate like parts in all the figures.

A represents a metal frame or stock constructed with a central opening to receive a 35 pair of cutters, B, of peculiar construction. Projecting from the longitudinal walls of said openings are central ribs or lugs, a, to support and guide the cutters placed thereon; 40 and to permit said cutters to be received within the central opening of the stock a groove, a^2 , is cut within one of the walls of said opening. The cutters B are grooved longitudinally at b on their sides to ride upon the rib a of the stock. The face of the cutters is also grooved longitudinally at b^2 to form cutting-teeth 1 2 on the edge of said groove, and to produce cutting teeth or edges of any desired length the face of each of the 50 teeth is relieved or beveled away from the

point or cutting-edge of the teeth in such a manner as not to interfere with each other. The highest part of the tooth 1 is along the edge of the groove b^2 , while the highest part of the tooth 2 is along the edge b^3 , upon which 55 two pairs of teeth will meet when forced close together.

Alongside the cutters B are placed the screw-cutting dies L C R. The screw-die L carries one-half of a left-hand thread-cutting nut. 60 The screw-die R carries one-half of a right-hand thread-cutting nut, and the screw-die C carries one-half of a right-hand nut on one side and one-half of a left-hand nut on the other. These screw-cutting dies, and also 65 the cutters B, are retained tightly together by means of the screw on the handle B^2 of the stock. By unscrewing said handle the thread-cutting opening between the dies L, C, and R, and also the opening b^4 between the pairs 70 of cutters B, can be made of any desired size to suit the different diameters of the axles. This hole b^4 is made conical, to prevent its walls coming in contact with or burring the thread on the screw at any point except at 75 the cutting-edge forming the collar upon the axle-spindle.

In operation the nut d is first removed from the end of the axle, Fig. 6, the cutters B are adjusted to the diameter of the screw d^2 , and 80 brought close to the shoulder d^3 on said axle. The nut d is then replaced against the back 85 of the cutters. Then by revolving the stock A, and at the same time tightening up the nut d as fast as the tool cuts off the metal, a proper length is given to the axle. The tool 90 is then removed therefrom, and the screw-cutting dies R or L (right or left) are applied and made to cut as much thread on the axle as the cutters had removed of metal from the shoulder d^3 , and the wheel can be replaced on the axle.

Having now fully described my invention and its operation, I claim—

1. The combination of a stock, A, provided 95 with internal ribs, a, with twin cutters B, having longitudinal grooves b and b^2 , cutting-teeth 1, beveled downwardly from the groove b^2 , and teeth 2, beveled from the edge b^3 , substantially as and for the purpose described. 100

2. The combination of the stock A, provided with internal ribs, cutters B, having longitudinal grooves b^2 , cutting-teeth 1 and 2, beveled as described, and a conical opening, 5 b^4 , between said grooves and cutters, substantially as and for the purpose described.

3. The combination of the stock A, provided with internal ribs, cutters B, having longitudinal grooves b^2 and a conical open-

ing between them, with screw-cutting dies, 10 and a screw-handle, B^2 , substantially as and for the purpose described.

In testimony whereof I affix my signature in presence of two witnesses.

EDWARD F. DALTON.
